DESIGN FOR A COIN CONTAINER

Denison Babcock, New York, N. Y.

Application February 12, 1936, Serial No. 61,110

Term of patent 3½ years

To all whom it may concern:

Be it known that I, Denison Babcock, a citizen of the United States of America, residing at New York city, in the county of New York, Borough of Manhattan, and State of New York, have invented a new, original, and ornamental Design for a Coin Container of which the following is a specification, reference being had to the accompanying drawing, forming a part thereof.

I claim:—

The ornamental design for a coin container as shown.

DENISON BABCOCK.
